UNITED STATES PATENT OFFICE.

DANIEL F. McGOVERN, OF MONTPELIER, VERMONT, ASSIGNOR TO C. C. PUTNAM, EXECUTOR OF PRENTICE C. WRIGHT, DECEASED, AND ADMINISTRATOR OF MEDAD WRIGHT, DECEASED.

POLISHING-WHEEL.

1,105,089.

Specification of Letters Patent. Patented July 28, 1914.

Application filed September 18, 1913. Serial No. 789,668.

To all whom it may concern:

Be it known that I, DANIEL FREDERICK McGOVERN, a citizen of the United States, residing at Montpelier, in the county of Washington and State of Vermont, have invented certain new and useful Improvements in Polishing-Wheels, of which the following is a specification, reference being had therein to the accompanying drawing.

10 The polishing-wheel provided by this invention is designed particularly for use with emery or other abrasive in smoothing and polishing granite, marble, or other stone, and it also may be used on other materials.

15 The device includes flanges or scrolls that are held together in the proper relative positions without the employment of a disk, and the flanges or scrolls are uncovered except over small areas where they are attached to a cross member. This makes it convenient to place abrasive from the top of the wheel between the scrolls where it is available for action between them and the surface being treated; and, when the 20 abrasive is spread over the surface being treated, it has a tendency to work upwardly from between the scrolls and off the top of the wheel and to return to the surface, whereby a substantially continuous movement of abrasive is maintained and the 25 efficiency of action enhanced. The particular construction and arrangement of the flanges or scrolls of the wheel are such that during rotation the centrifugal tendency of abrasive 30 to be thrown from under the wheel is counteracted and the abrasive is kept where it is capable of efficient action against the surface being treated, and the wheel has been found in practice to cause a more equal distribution of abrasive than in wheels commonly in use.

The construction of the wheel and arrangement of its parts will be apparent from the accompanying drawing, forming part 45 hereof, wherein a preferable embodiment is disclosed, for purposes of illustration.

While the embodiment shown now is considered a preferable one, it is to be understood that it is not the intention to be limited necessarily to the exact arrangement disclosed, as it is obvious that such changes as are within the limits of the claims can be made without departing from the nature and spirit of the invention.

55 Like reference-characters refer to corre-

sponding parts in the views of the drawing, of which—

Figure 1 is a top view of the polishing-wheel; Fig. 2 is a side view; and Fig. 3 is a bottom view.

Having more particular reference to the drawing, 4 designates diametrically-positioned cross members, which extend from the periphery sufficiently near to the center of the wheel to connect with the inner scrolls mentioned hereinafter. In order to afford a connecting means at or near the center of the wheel for a shaft or other element for rotating the wheel over a surface being treated, a member or bar 5, spanning the 60 space at the center between the cross members and within the inner scrolls, is attached to those members by bolts 6, or the cross members and member 5 may be formed integrally. The cross members constitute a holding means for the ring and scrolls mentioned hereafter.

An outer annular ring 7 is secured to the under sides of the cross members at or near their outer ends, and within the ring 80 there are a plurality of spiral scrolls 8. The under sides of the ring and scrolls are in the same plane, and the cross members are comparatively narrow so that they cover only small portions of the scrolls.

The scrolls are of sufficient length and curve to extend from one cross member to the other, to which portions they are secured at their ends and held in spaced substantially parallel relation so that there are channels 9 between them, which are open at the top.

Although there may be one or any other desired number of sets of scrolls and more than one set of cross members, in the embodiment shown in the drawing as illustrative of the principles of the invention, one set of cross members and two sets of scrolls are used, the scrolls of each set from the periphery of the wheel toward the center being designated by the characters A, B, C, and D.

The scrolls are so arranged and curved that the rear end of every scroll of a set has position nearer the center of the wheel than the front end of the corresponding scroll of the other set, so that all scrolls of each set, except the two inner ones D, terminate in front of the channels between the corresponding scrolls of the other set and 110

the scrolls next inwardly thereof. This arrangement imparts to abrasive discharged at the end of one channel a tendency to go into a channel of the next succeeding set 5 that is nearer the center of the wheel, and thus the tendency of abrasive to be thrown from under the wheel under centrifugal influence to a great extent is nullified.

The cross members, ring, and scrolls in 10 practice preferably are cast as an integral unit. However, if desired, the parts may be formed separately by casting, forging, or otherwise, and connected by any suitable means to form a complete wheel.

15 Having thus described my invention, what I claim as new, and desire to secure by Letters Patent, is—

1. A polishing-wheel comprising a holding member, and sets of scrolls secured

thereto having channels therebetween, the 20 parts being so arranged that some scrolls of a set terminate in front of the channels between the corresponding scrolls of another set and the scrolls next inwardly thereof.

2. A polishing-wheel comprising a holding member, and sets of scrolls secured thereto having channels therebetween that are open at the top, the parts being so arranged that some scrolls of a set terminate in front of the channels between the corresponding scrolls of another set and the scrolls next inwardly thereof. 25 30

In testimony whereof I affix my signature in presence of two witnesses.

DANIEL F. McGOVERN.
